UNITED STATES PATENT OFFICE.

WILLIAM P. BENHAM, OF HARTFORD, CONNECTICUT, ASSIGNOR TO THE
POPE MANUFACTURING COMPANY, OF SAME PLACE.

VELOCIPED.

SPECIFICATION forming part of Letters Patent No. 310,776, dated January 13, 1885.

Application filed December 8, 1884. (No model.)

To all whom it may concern:

Be it known that I, WILLIAM P. BENHAM, of Hartford, Connecticut, have invented certain new and useful Improvements in Velocipedes, of which the following is a specification.

My improvements relate to those parts of velocipedes, whether of bicycles or tricycles, called "steering-heads" and "handle-bars," 10 and the attachments of the same. The nature of them will be apparent from the following description, taken in connection with the drawings, in which—

Figure 1 shows in front elevation and part 15 section a velocipede-steering head and part of a handle-bar embodying my improvements in one form. Fig. 2 shows the same in a vertical section on the line $x-x$ in Fig. 1, the dotted line $y-y$ in Fig. 2 showing a line of section 20 at right angles to that in Fig. 1. Fig. 3 shows, on a smaller scale, and in elevation, the same devices with a handle-bar. Fig. 4 shows similar contrivances to those represented in Fig. 1, with certain modifications of my improvements, which will be herein described.

A is a cylindrical steering-head of a bicycle.

a is the open or internal slot in which the spindle-bearing or steering-centers may be 30 operated.

a' is the threaded aperture in the top of the head for the set-screw which adjusts the steering centers.

B is a handle-bar, which may be either solid 35 or tubular, and which I prefer to make of one continuous bar or rod, to the extremities of which are attached the handles B², and to the middle of which I attach or form upon it the detent D. This detent D being rigidly attached to the handle-bar and shaped so as to 40 meet certain sides of the slot d', serves not only to locate the handle-bar evenly and quickly by an even division of its length on either side the middle line of the head, but also to prevent the handle-bar when in position from turning or revolving on its axis.

E is that part or enlargement of the steering-head A which constitutes the handle-bar lug, and has a horizontal slot or opening

through it at right angles to the vertical axial 50 line of the steering-head, which I make of just sufficient breadth to allow of the introduction of the handle-bar, or, in other words, of about the breadth of the diameter of the handle-bar, and also with jaws ee.

C are sleeve-nuts, having the free portion c adapted to surround the handle-bar, on which may be serrations and corners and sides for the application of a wrench, and threaded portions c² c² adapted to engage with threaded portions b b of the lug E.

It will be apparent that with the construction, as shown and described, the sleeve-nuts C C may be placed upon the handle-bar B, one upon either end, and are movable toward the middle or detent, D. The handle-bar with these sleeve-nuts upon it may be brought in front of and hard toward the middle of the lug E, so that the detent D shall engage in the slot d', and the handle-bar pass into the slot d, 70 and the handle-bar B correctly located as to its length and other points of position, and then the nut C on either side the lug may be brought up and screwed onto the projection b to form a secure fastening device to hold the 75 handle-bar rigidly in position. Again, by unscrewing the sleeve-nut on either side of the lug E the handle-bar may be easily removed.

Fig. 4 shows certain modifications of this plan. Instead of the projection b of the lug E 80 upon the sleeve-nut C, when it is in position, I have the projection b', which surrounds a portion of the sleeve-nut C, and instead of having the threaded portion of the lug to engage with the internal thread of the nut C, I 85 have the threaded portion b' of or upon the handle-bar B' to engage with an internal thread in the sleeve-nut C'. I show the nut C' as prepared for operation by the hand instead of a wrench. This construction shows 90 substantially the same parts and operates substantially in the same way, although the sleeve-nut forms a lock on the inside of the projection of the lug instead of on the outside. In either form the objects of my improvements are obtained—viz., a secure and 95 detachable handle-bar in one continuous piece, easily and securely fixed in position, whether

the bar be solid or hollow, curved, or straight. It is obvious that other modifications in form may be made without departing from my invention, and I do not wish to be limited 5 strictly to the forms shown.

I claim as new and of my invention—

1. The combination of an undivided bar, and an open-slotted lug, and two sleeve-nuts, or their equivalents, one on either side the 10 lug, surrounding the bar and adapted to lock it rigidly to the lug, essentially as set forth.

2. The described improvement in handle-bar lugs for velocipede-steering heads, consisting in an open slot, *d*, between the two 15 jaws *e e* of the lug, for admission of a continuous handle-bar, and projections *b b*, or their equivalents adapted to receive and be com-

bined with sleeve-nuts for retaining the handle-bar securely in place and for allowing it to be removed, essentially as set forth. 20

3. In combination with the handle-bar *B*, the detent *D*, constructed and adapted to operate substantially as and for the purposes set forth.

4. The combination, in a velocipede, of lug 25 *E*, having jaws *e e*, slots *d d' d'*, and projections *b b*, or their equivalents, a continuous handle-bar, *B*, detent *D*, and sleeve-nuts *C C*, or their equivalents, essentially as set forth.

WILLIAM P. BENHAM.
